UNITED STATES PATENT OFFICE

123,462

DESIGN FOR A SHEET MATERIAL DISPENSER

A. Edward Pollock, New York, N. Y.

Application March 7, 1940, Serial No. 90,753

Term of patent 3½ years

To all whom it may concern:

Be it known that I, A. Edward Pollock, a citizen of the United States of America and residing at New York, county of New York, State of New York, have invented a new, original, and ornamental Design for a Sheet Material Dispenser, of which the following is a specification, reference being had to the accompanying drawing, forming part thereof.

In the accompanying drawing:
Fig. 1 is a perspective view of a sheet material dispenser showing my new design,

Fig. 2 is a side elevational view thereof, and
Fig. 3 is a top plan view.

I claim:

The ornamental design for a sheet material dispenser, as shown.

A. EDWARD POLLOCK.
